UNITED STATES PATENT OFFICE.

FREDERICK NEWHOUSE, OF TOLEDO, ASSIGNOR TO THE HARRIS METAL WHEEL COMPANY, OF AUBURNDALE, OHIO.

VEHICLE-WHEEL.

SPECIFICATION forming part of Letters Patent No. 425,240, dated April 8, 1890.

Application filed September 24, 1889. Serial No. 324,890. (No model.)

To all whom it may concern:

Be it known that I, FREDERICK NEWHOUSE, a citizen of the United States, residing at Toledo, in the county of Lucas and State of Ohio, have invented certain new and useful Improvements in Vehicle-Wheels, of which the following is a specification, reference being had therein to the accompanying drawings.

10 This invention relates to new and useful improvements in vehicle-wheels of that class in which the spokes are made in pairs, each pair being made of one rod or wire bent at its center and secured in this bend upon the hub, 15 the ends thereof being secured in spoke-seats in the hub; and the invention consists in the peculiar construction of the hub and the spoke-seats, whereby the spokes may be secured upon the hub in the most simple and 20 expeditious manner, and whereby they are held there without danger of displacement, all as more fully hereinafter described.

In the drawings which accompany this specification, Figure 1 is a vertical section 25 through the wheel containing my improvements and showing the hub in elevation. Fig. 2 is a front perspective view of one of the hub-sections detached, showing the manner of attaching the spoke-wires thereto. Fig. 3 is a front elevation thereof with the wires in place. Fig. 4 is a rear elevation thereof. Fig. 5 is a cross-section on line X X in Fig. 3, and Fig. 6 is a cross-section on line Y Y in Fig. 3.

A is a box or hub having thereon suitable 35 shoulders B.

C are hub-sections sleeved upon the box A and abutting against the shoulders B. These are held in position, preferably, by being forced on, the usual tinning process in such 40 metal wheels adding the necessary stability.

D are the spokes, which are formed in pairs, each pair being formed of a single wire. These are secured at their outer ends to the rim or tire E, and at their inner ends engaging over 45 the lugs F upon the hub-sections C.

G is a forwardly and outwardly extending flange on the hub-section, provided with segmental circular apertures H, (one for each pair of spokes,) and located with their edges 50 in line with the sides of the lugs F. These

flanges are provided with suitable wire-passages I, arranged in line with the wire-passages J on the body of the hub-section, each pair of the wire-passages being connected by the apertures H. The parts being thus constructed, the hub-section being sleeved upon the box A and secured thereon in any desired manner, in order to secure the spokes thereto, the spokes being bent into pairs, the bent end K of the spokes is inserted through 60 the apertures H, as shown at L in Fig. 2, and then lowered to engage over the end of the lug, which is provided with the cut-away portion M, into which the loop of the wire engages. All of the spokes being thus engaged 65 upon the hub-sections and their ends secured upon the tire in the well-known manner, my wheel is now complete. It will be seen that the wire has three points of bearing, the end of the bend engaging in the cut-away portion 70 M, the straight portion engaging in the wire-passage J in the body of the hub-section, and in the wire-passages I in the flange G. If desired, the hub A may be extended some distance through the hub-section and a collar 75 or sleeve N forced thereon, abutting with its outer edge against the ends of the wire spokes, as shown in Fig. 5, thereby preventing their disengagement. Should a spoke become 80 broken or weak, and should it be desired to remove it, it may be accomplished by disengaging the spoke at its ends and reversing the operation of disengaging the loop in the spoke from the lug F.

This construction of wheel does away with 85 the disadvantage which has existed in previous constructions of being obliged to thread the wire spoke through apertures in the hub-sections, and allows of manufacturing the wheel with much greater economy in time, 90 without sacrificing in any degree the strength and rigidity of the same. It also allows of more readily repairing the wheel in case it should become broken. If desired, any ornamental cap may be placed over the outside 95 of the hub.

What I claim as my invention is—

1. In a wheel, the combination, with a box or hub and united spokes, of hub-sections secured thereon formed with openings, through 100

which the bent end portion or butts of the spokes are without altering their shape passed, and lugs formed at the base of said openings on which the butt-ends of the spokes rest, substantially as described.

2. In a wheel, the combination, with a box or hub and united spokes, of hub-sections thereon formed with openings H, through which the bent ends of the spokes pass, lugs F, on which the spokes rest, and radial grooves

in the side face of the rim of the sections in which the spokes rest, substantially as described.

In testimony whereof I affix my signature, in presence of two witnesses, this 4th day of September, 1889.

FREDERICK NEWHOUSE.
